UNITED STATES PATENT OFFICE

156,145

DESIGN FOR A MOP WAGON

George F. Minnis, Chicago, Ill.

Application December 17, 1948, Serial No. 150,202

Term of patent 14 years

(Cl. D14—3)

To all whom it may concern:

Be it known that I, George F. Minnis, a citizen of the United States, residing at Chicago, in the county of Cook and State of Illinois, have invented a new, original, and ornamental Design for a Mop Wagon, of which the following is a specification, reference being had to the accompanying drawing, forming a part thereof.

In the drawing:

Fig. 1 is a perspective view of a mop wagon embodying my new design.

Fig. 2 is a top plan view of the mop wagon of Fig. 1.

The opposite sides of the tank are similar to those shown in Fig. 1.

I claim:

The ornamental design for a mop wagon, as shown and described.

GEORGE F. MINNIS.
